(57) **CLAIM**

The ornamental design for a hydrogen fuel cell module for power generation, as shown and described.

DESCRIPTION

1. Hydrogen fuel cell module for power generation

1.1 : Perspective

1.2 : Front

1.3 : Back

1.4 : Right

1.5 : Left

1.6 : Top

1.7 : Bottom

1.8 : Perspective

Fig. **1.1** is a top, front, and left side perspective view of a hydrogen fuel cell module for power generation embodying our new design; fig. **1.2** is a front elevation view thereof; fig. **1.3** is a rear elevation view thereof; fig. **1.4** is a right side elevation view thereof; fig. **1.5** is a left side elevation view thereof; fig. **1.6** is a top plan view thereof; fig. **1.7** is a bottom plan view thereof; and fig. **1.8** is a rear, top, and right side perspective view thereof.
